US0D1020985S

(12) **United States Design Patent** (10) **Patent No.:** **US D1,020,985 S**
(45) **Date of Patent:** **** Apr. 2, 2024**

(54) **WATER FILTER**

(71) Applicant: **Senwater Tech. (Shanghai) CO., Ltd.**,
Shanghai (CN)

(72) Inventor: **Haijun Yang**, Shanghai (CN)

(73) Assignee: **SENWATER TECH. (SHANGHAI)
CO., LTD.**, Shanghai (CN)

(**) Term: **15 Years**

(21) Appl. No.: **29/843,793**

(22) Filed: **Jun. 23, 2022**

(51) LOC (14) Cl. **23-01**

(52) U.S. Cl.

USPC **D23/207**

(58) **Field of Classification Search**

USPC **D23/207, 208, 209, 210; D24/162
CPC ... B01D 2201/30; B01D 2221/02; C02F 9/20;
C02F 2307/10; A47J 31/605**

See application file for complete search history.

(57) **CLAIM**

The ornamental design for a water filter, as shown and described.

DESCRIPTION

FIG. 1 is a perspective view of the water filter showing the design;

FIG. 2 is a front view of the water filter showing the design;

FIG. 3 is a back view of the water filter showing the design;

FIG. 4 is a right view of the water filter showing the design;

FIG. 5 is a left view of the water filter showing the design;

FIG. 6 is a top view of the water filter showing the design; and,

FIG. 7 is a bottom view of the water filter showing the design.

1 Claim, 7 Drawing Sheets
